UNITED STATES PATENT OFFICE

136,161

DESIGN FOR A COMBINED SHADE AND CURTAIN BRACKET

Ilion Ilieff, Detroit, Mich.

Application June 2, 1943, Serial No. 110,344

Term of patent 7 years

To all whom it may concern:

Be it known that I, Ilion Ilieff, a citizen of the United States, residing at Detroit, in the county of Wayne and State of Michigan, have invented a new, original, and ornamental Design for a Combined Shade and Curtain Bracket, of which the following is a specification, reference being had to the accompanying drawing, forming part thereof.

I claim:

The ornamental design for a combined shade and curtain bracket, as shown.

ILION ILIEFF.
